[57] CLAIM

The ornamental design for a car caddy, as shown and
described.

DESCRIPTION

FIG. 1 is a front perspective view of a car caddy em-
bodying my new design;

FIG. 2 is a side elevational view thereof;

FIG. 3 is a front elevational view thereof;

FIG. 4 is a top plan view thereof;

FIG. 5 is a front perspective view similar to FIG. 1, but
with the cover of the top compartment shown in an
open position; and,

FIG. 6 is a vertical sectional view taken substantially
along line 6—6 in FIG. 4.

FIG. 1.FIG. 2.FIG. 3.FIG. 4.

FIG. 5.

FIG. 6.
